SAMUEL GANTZ, OF BEAVER CREEK, MARYLAND.

Letters Patent No. 90,520, dated May 25, 1869.

IMPROVED MOP-HEAD.

The Schedule referred to in these Letters Patent and making part of the same.

To all whom it may concern:

Be it known that I, SAMUEL GANTZ, of Beaver Creek, in the county of Washington, and State of Maryland, have invented a new and improved Mop-Head; and I do hereby declare that the following is a full, clear, and exact description of the construction and operation of the same, reference being had to the accompanying drawings, making a part of this specification, in which my invention is represented by a side view, a portion of the movable jaw being shown in section.

The object of this invention is to provide for public use a simple and cheap mop-head, which can be conveniently operated, and which will hold the mop securely.

In the drawings—

A is the handle, and B is an immovable jaw fixed on the lower end of the handle, and roughened, or provided with serrated teeth *b b*, on its inner side.

C is a jaw of similar shape to B, and having its rough face adjacent to that of the latter, but sliding freely on the handle, which extends through a slot in it, slightly larger than the handle, as seen at *m*, so that when the mop, shown in red, is inserted between the jaws, and the part C is forced down, the movable

jaw will clamp itself upon the handle, and the elastic expansive pressure of the mop will keep it clamped firmly.

D is a wire rod, attached to the movable jaw C, and serving as a handle, by which to force the latter down and clamp the mop in place, and by which to draw the movable jaw up again and release the mop.

This part D is preferably, in form and construction, a single metallic rod, looped at *d d*, bent partially around the handle at *d'*, and extending through guides *e e*, attached to the handle.

Having thus described my invention, What I claim as new, and desire to secure by Letters Patent, is—

The mop-head, above described, consisting essentially of the handle A, fixed jaw B, movable jaw C, having a slot, *m*, slightly larger than the handle A, and rod D, constructed and operating substantially as and for the purposes set forth.

To the above specification of my improvement, I have set my hand, this 7th day of April, 1869.

SAMUEL GANTZ.
